TRANSFORMER WINDING SUPPORT

Donald G. McArn, Pittsburgh, Pa., assignor to
Allis-Chalmers Manufacturing Company, Mil-
waukee, Wis., a corporation of Delaware

Application December 3, 1937, Serial No. 177,932

2 Claims. (Cl. 242—119)

This invention refers in general to supports for electrical windings and particularly to supports for plural section windings providing definite insulated spaces into which coil sections can be wound quickly and economically.

Supports or forms on which several sections of magnetizing windings have been wound have been molded from solid insulating material. This molding process required expensive molds and machinery and simple changes in size and form were not easily made. The product, if made of synthetic materials of high dielectric strength and oil resistivity, lacked flexibility and therefore was easily breakable.

Pressed board and similar sheet insulating material have high dielectric strength at elevated temperatures. The dielectric strength of the ordinary moldable synthetic materials decreases as the temperature is raised. Flexible sheet material is easily handled and can be stocked in rolls, thereby using little storage space. Its unit dielectric strength is high, thereby permitting, in transformer windings, the use of a thin insulating wall between high and low voltage windings and consequently low reactance in the transformer. By utilizing such material for coil forms, it is a simple matter to change the size or number of coil section spaces.

It is therefore an object of this invention to provide an improved winding support which avoids the above disadvantages and obtains the above advantages.

It is also an object of the present invention to provide an improved support for plural section windings which will have sufficient rigidity to support the coil sections and will have sufficient flexibility to avoid breakage.

It is also an object of this invention to provide a support made cheaply and economically from sheet insulating material.

It is a further object of the present invention to provide a support of the above type with improved insulation between coil sections.

Objects and advantages other than those above set forth will be apparent from the following description, when read in connection with the accompanying drawing, in which:

Fig. 1 is a sectional view of a coil support embodying the present invention;

Fig. 2 is a sectional view of the support of Fig. 1, taken on the line II—II.

The winding support or spool shown in the drawing is built up entirely from suitable flexible sheet insulating material, such as pressed board,

and bound together by a binder such as shellac. Sheets of from twenty thousandths to forty thousandths of an inch in thickness have been found satisfactory, however, the invention is not limited to a particular material or size.

The spool shown is formed by winding two layers 5 of sheet material on a cylindrical mandrel with a small amount of shellac or similar binder between the layers to hold them in place on the mandrel. Several layers 6 of similar material having longitudinal slits forming tabs 7 in each end thereof are then applied in a similar manner and the tabs 7 thereof bent at right angles to the longitudinal axis of the spool and shellacked together. The exact width of the tabs 7 or end portions 7 depends upon the diameter of the spool, the width being such that a whole number of tabs 7 and a fractional tab 7 are included in a single layer 6. Thus, in any layer 6 the slits between tabs 7 are staggered relative to the slits in the adjacent layer 6. In other words, the slits in one layer 6 are adjacent approximately the center of a tab 7 in the adjacent layer 6. The depth of the slits is dependent upon desired depth of the coil section.

Annular sheets 8 and 9 of thicker, more rigid insulating material are placed in the position shown and bound to the end portions 7 with shellac. The sheet 8 is placed immediately surrounding and flush with ends of the innermost layers 5.

One layer 11 having end portions 12 and 13 between slits similar to those in the ends of layer 6 is then applied to the spool and the end portions 12 bent at right angles and bound to annular sheet 8. Annular rings 14 and 15 are then applied over the unbent end portions 13 of layer 11 and ring 14 is bound to the bent portions 12, completing the assembling of one end of coil section 10.

The end portions 13 are now bent and bound to ring 15 and ring 16 is applied and bound to portions 13. A layer 21, similar to layer 11, is similarly applied and the end portions 22 bound to ring 16 so that the slits therebetween are staggered relative to the slits between portions 13 of layer 11. Ring 23 is applied and bound, thereby completing the insulation between coil sections 10 and 20. Coil sections 30 and 40 are similarly assembled. As soon as the shellac has dried, the assembly becomes very rigid but with sufficient flexibility remaining to prevent breakage of the spool.

When used in transformer windings, the high

voltage winding is wound in sections 10, 20, 30 and 40 and the spool mounted on a core 41 having a low voltage winding 42 thereon wound to the diameter of the layer 5. The end turns of coil section 20 are insulated from the adjacent end turns of coil section 10 by solid insulation of rings 15, 16 and 23. A long creepage voltage path is formed due to the staggering of adjacent end portions 22 and 13. The outer end portions of coil section 10 are similarly insulated from the outer end turns of the low voltage coil and from the core.

The support above described incorporates in one spool, assembled from sheets of flexible insulating material bound with shellac, the major insulation between high and low voltage windings, between high voltage coil sections and between high voltage coil ends and the core. The coil section spaces are definite and rugged. It is obvious that changing the size of the spool, the number or depth of sections, or the amount of any insulation, can be very simply effected by mere change in size of the sheets.

In winding the coil sections, end 33 of a conductor is inserted in hole 31 in the partition between coil sections 10 and 20 and end 34 of a conductor is inserted in a similar hole in the partition between coil sections 30 and 40. Coil sections 10 and 30 are then wound simultaneously by rotating the spool in a given direction. The spool is then reversed on the mandrel, the ends of the conductor spliced to ends 33 and 34 in sections 20 and 40, and these sections then wound by rotating the spool in the same direction. This method permits of simple, extremely rapid, automatic machine winding. Any number of coil sections may be used and alternate sections wound simultaneously.

The end slits of the sheets 6 and 11 have been described and shown as longitudinal, however, these slits may be at an angle to the longitudinal axis if desired.

Although but a few embodiments of the present invention have been illustrated and described, it will be apparent to those skilled in the art that various changes and modifications may be made therein without departing from the spirit of the invention or the scope of the appended claims.

It is claimed and desired to secure by Letters Patent:

1. A unitary plural section winding form comprising in combination, a first cylindrical sheet of thin flexible insulating material provided at each end thereof with circumferentially spaced slits, means for rigidly maintaining the portions between said slits at substantially right angles to the longitudinal axis of said sheet to form end flanges of said winding form, a plurality of additional cylindrical sheets of flexible insulating material each positioned on said first sheet and each provided at an end thereof with circumferentially spaced slits, and means for rigidly joining the portions between the slits of one additional sheet in staggered relation to portions between the slits of an adjacent additional sheet for maintaining said portions of said additional sheets at substantially right angles to said first sheet to form a flange intermediate said end flanges and spaced therefrom, said joining means comprising a disk of sheet insulating material between said portions of said additional sheets, said joining means further comprising a binding material. 25

2. A unitary plural section winding form comprising in combination, a first cylindrical sheet of thin flexible insulating material provided at each end thereof with circumferentially spaced slits, means for rigidly maintaining the portions between said slits at substantially right angles to the longitudinal axis of said sheet to form end flanges of said winding form, a plurality of additional cylindrical sheets of flexible insulating material each positioned on said first sheet and each provided at both ends thereof with circumferentially spaced slits, and means for rigidly joining the portions between the slits of one additional sheet in staggered relation to portions between the slits of an adjacent additional sheet for maintaining said portions of said additional sheets at substantially right angles to said first sheet to form a flange intermediate said end flanges and spaced therefrom, said joining means comprising a disk of sheet insulating material between said portions of said additional sheets, said joining means further comprising a binding material. 30 35 40 45
